CONDENSER TUBE PACKING

Samuel Pennella, East Orange, N. J.

Application January 7, 1944, Serial No. 517,316

18 Claims. (Cl. 285—45)

1

This invention relates to surface condensers or heat exchangers of the surface type embodying tubes through which one of the fluids to be brought in heat exchange relationship flows, and more particularly to sealing means or packing for forming a fluid tight seal between the ends of the tubes and the tube sheets of such an apparatus.

The packing or sealing means forming the present invention is particularly adaptable for use in surface condensers or heat exchange devices such as disclosed in my prior Patent No. 2,298,154, issued October 6, 1942, although it is adaptable for use with any approved type of condenser or heat exchange apparatus of the surface type; and the present invention constitutes an improvement over the packing or sealing means shown in said Letters Patent. Also the packing or sealing means of the present application constitutes an improvement over the analogous means disclosed in my companion application Serial No. 479,831.

An object of the present invention is to provide packing for the tubes of heat exchangers of the surface type which may be marketed as a complete assembled unit for packing one end of a tube, and which may be driven, as a unit, into the tube receiving bore of a tube head of the tube sheet by the use of an ordinary hammer and a simple mandrel, eliminating the use of special tools, wrenches, or the like, and also very materially reducing the time and labor required for packing a tube.

Furthermore, it is an object of the present invention to provide a packing structure as specified which, owing to its particular construction and the material of which it is constructed, may be made in complete units in standard sizes, such standard sizes being effective to seal tube and tube sheets within predetermined ranges such as in the event that the countersinks in the tube heads or tube sheets are over size or under size, thereby eliminating the manufacture of many odd sizes of packing.

In tube packings of the type disclosed in my companion application, Serial No. 479,831, embodying a fiber member swellable on wetting, a short interval of time will elapse after water is first passed through the tubes before the fiber will swell sufficiently to form a fluid-tight seal, thus permitting leakage of the water or coolant from the tubes into the interior of the heat exchange device for a short period of time following the initial starting up of the apparatus. This is particularly undesirable in instances where the condenser is connected in a power system and replacement tubes are being installed.

2

An object of the present invention is to provide a packing for condenser or heat exchange tubes which will instantly form a fluid-tight seal, upon its installation, between the packing and tube head and between the tube and packing, thus eliminating the short period of leakage above referred to, and a packing structure which will, through distortion of the swellable fabric sleeve, prevent displacement of the packing structure during the interval between its insertion between the tube sheet and its swelling to a sufficient extent to cause it to be tightly sealed in place.

A further object of the present invention is to provide a tube packing as specified which employed in surface condensers of the type disclosed in my prior Patent No. 2,298,154 will effectively form fluid seals about the tubes and permit the tubes to be driven through the packing structure without disrupting the fluid seals or fluid-tight joints between the tube packing and the tube heads.

With these and other objects in view, as may appear from the accompanying specification, the invention consists of various features of construction and combination of parts, which will be first described in connection with the accompanying drawings, showing a condenser tube packing of a preferred form embodying the invention, and the features forming the invention will be specifically pointed out in the claims.

In the drawings:

Figure 1 is a view in fragmentary longitudinal section showing the improved packing structures for use on the inlet and outlet ends of tubes in a surface condenser or heat exchange apparatus.

Figure 2 is a view partly in section and partly in elevation of the packing structure employed at the inlet ends of the tubes, prior to its insertion into a tube sheet and showing it as it is assembled for marketing.

Figure 3 is an end view of the structure shown in Figure 2.

Figure 4 is a view partly in longitudinal section and partly in elevation through the improved type of packing employed at the inlet ends of the tubes showing how a part of this packing is distorted to form a seal and to hold the packing in place immediately after it has been driven into a tube head.

Figure 5 is a view partly in longitudinal section and partly in elevation of the improved packing such as is employed at the outlet end of the tubes.

Figure 6 is an end view of the packing shown in Figure 5.

Figure 7 is a view partly in longitudinal section

and partly in elevation showing the packing structure employed at the outlet end of the tubes immediately before it has been driven into position and distorted.

Figure 8 is a longitudinal section through a modified form of the packing such as employed at the inlet ends of the tubes.

Figure 9 is a longitudinal section through the modified form of packing shown in Figure 8 illustrating it in position in a tube sheet.

Figure 10 is an end view of an expanding ring employed in the modified form of packing shown in Figure 8.

Figure 11 is a longitudinal section through a modified form of the packing such as is used at the outlet ends of the tubes.

Figure 12 is an end view of the modified form of the packing shown in Figure 11.

Figure 13 is a longitudinal sectional view through a further modified form of the improved packing structure showing it in place in a tube sheet.

Figure 14 is a longitudinal section through the modified form of the improved packing structure showing it prior to its insertion in place in a tube sheet.

Figure 15 is an end view of the modified form of packing.

Figure 16 is a longitudinal section through the fiber sleeve employed in the modified form of packing.

Referring more particularly to the drawings, a tube such as is used in surface condenser or analogous heat exchange apparatus is shown at 1 and the ends of this tube, as is usual in the construction of such apparatus, extend through the tube heads or tube sheets 2 and 3 which are positioned at the inlet and outlet ends of the tubes, respectively. The packing structure which in combination with the manner of forming the countersinks in the tube heads or tube sheets 2 or 3 constitute the present invention are shown in section at the inlet and outlet ends of the tubes. In other particulars the packing employed at the outlet ends of the tubes is similar to that employed about the inlet ends of the tubes although the two structures differ somewhat in detail.

The packing structure employed at the inlet ends of the tubes is illustrated specifically in Figures 2 to 4 of the drawings and it comprises a cylindrical coil 4 of soft collapsible packing which may be corset lacing or any other approved material and which carries a lubricant so as to permit not only a firm sealing engagement with the outer surface of the tubes, but to provide sufficient lubrication to permit the tubes to be driven through the packing or sealing structures without disrupting the fluid-tight seal when the packing structures are employed in a condenser or heat exchange apparatus embodying the principles disclosed and claimed in my Patent No. 2,298,154.

Fiber washers or rings 5 and 6 are placed at the opposite ends of the cylinder of soft collapsible packing, and a ferrule 7 which is preferably made of metal abuts against the outer end of the outer fiber ring 6; and it has an annular flange 8 on its outer end which serves as a contact surface for limiting the insertion of the packing into the countersunk bore or countersink 9 of the tube head 2. And it further provides an impact surface for facilitating the driving of the packing into position in the countersink 9.

Fiber rings 5 and 6, the cylinder of soft collapsible packing 4, and the main body of the ferrule 7 are all enclosed in a relatively thin cylinder 19

which is made of fiber of any suitable composition which will swell when wetted.

As clearly shown in Figure 1 of the drawings, the wall of the countersink 9 is corrugated or roughened as shown at 11, and such roughening may be spiral grooves, screw threads, or any other suitable type of roughening desired so long as it provides alternate recesses and raised portions.

It will be noted by particular reference to the drawings, that the packing structure is so constructed that the entire unit for sealing the inlet end of each tube in a surface condenser or heat exchange apparatus is assembled and may be marketed as a complete unit so that it may be slipped and driven into the countersink about the inlet end of a tube in its unitary structure thereby eliminating much time, labor and consequent expense such as is caused when threaded ferrules are employed to hold in place various types of packing structure which are inserted into the countersinks of the tube heads independently of the ferrules as has been the practice heretofore.

When the packing structure as a complete unit is driven into the countersink 9, after its inner 25 end engages the shoulder 12 formed by the inner end of the countersink, the packing is further driven inwardly by impact from an ordinary hammer, or if so desired by an air hammer sufficiently to cause a rupture of the relatively thin fiber enclosing sleeve 10. This rupture invariably occurs in the part of the sleeve which surrounds the soft collapsible packing, as clearly shown in Figures 1 and 4 of the drawings causing the sleeve to be forced outwardly as indicated at 14, engaging 30 in certain of the recesses of the roughened inner surface 11 of the countersink 9, acting as a temporary immediate liquid seal to prevent leakage of liquid until such time as the fiber enclosing sleeve 10 and the fiber rings 5 and 6 swell 35 through wetting to form the firm, secure fluid seal. This disruption of the fiber-containing sleeve 10 also prevents displacement of the packing until such time as it swells sufficiently to be thoroughly anchored in the countersink. The 40 rupture of the fiber-containing sleeve 10 caused by the compressing of the ring of the fiber sleeve also will cause the soft collapsible packing to be forced into fluid-tight engagement with the tube 1 to maintain a seal independently, until such 45 time as the fiber rings 5 and 6 swell to cooperate with the soft flexible packing to form the permanent fluid seal.

The packing structure employed for the discharge or outlet ends of the tubes 1 is, in its major respects, similar to the packing structure just described for use on the inlet ends of the tubes; however, it is slightly more simple in construction.

The packing structure which is shown at the right hand side of Figure 1 and Figures 5, 6, and 7 60 comprises a fiber sleeve 20, the outer end of which is relatively thick in comparison with the major portion of the sleeve, as shown at 21, providing an annular shoulder 22 against which one end of the cylinder 23 of soft collapsible packing 65 abuts. The soft collapsible packing 23 may be the same as the soft collapsible packing 4 heretofore described, and the inner end of the cylinder of soft collapsible packing engages against a fiber washer 24 which is inserted into the inner end of the reduced portion 25 of the sleeve 20. The sleeve 20 forms a containing sleeve similar to the containing sleeve 10, and the portion of this sleeve extending inwardly from the relatively thick outer end portion 21 thereof is comparatively thin so 70 that when the packing is driven into the counter-

sink 26 in the tube sheet 3 this sleeve will be distorted as shown at 27 and forced outwardly into some recesses of the roughened surface 28 of the countersink 26 as is clearly shown in Figure 1 of the drawings.

Figure 7 of the drawings illustrates the manner in which the packing structure is driven into the countersinks. It is first inserted into the countersink 26, since its outer diameter is such that it may be easily inserted by hand, and a mandrel 29 is then employed, the small cylindrical body 30 of which fits into the tube 1 while the head 31 of the mandrel engages the outer end of the sleeve 21. The packing is then driven or forced inwardly in the countersink by hammer blows against the head 31 causing the outward disruption of the thin enclosing portion 25 of the sleeve 20 and causing the soft pliable packing 23 to be forced into sealing engagement with the outer surface of the tube 1.

Figures 8 to 12 of the drawings show slight modifications in the packing structures for the inlet and outlet ends of the tubes of a condenser or analogous heat exchanger. And Figures 8 to 10 inclusive show the modified construction of the packing for use about the inlet ends of the tubes.

This modified construction of the packing comprises a cylinder of soft collapsible packing 33 which may be of any suitable type of soft collapsible packing such as referred to in Figures 1 to 7 inclusive. This packing is surrounded or enclosed within a fiber-containing sleeve 34 which is constructed of fibrous material which will swell when wetted, and which may be distorted by impact a slight distance radially without breaking. The containing sleeve 34 as clearly shown in Figures 8 and 9 of the drawings projects beyond each end of the cylinder 33 of soft collapsible packing, and a fiber washer 35 abuts against the outer end of the cylinder 33, while a second fiber washer 36 abuts against the inner end of the sleeve 34. These fiber washers 35 and 36 are made of material swellable when wetted and are preferably made of the same material as a relatively thin containing sleeve 34. As shown in Figure 8 of the drawings, the sleeve 36 in the inner end of the packing is tapered, gradually increasing in diameter as it extends outwardly from the inner end of the sleeve 34, and prior to the packing being driven in place within a tube sheet, this sleeve 36 projects a short distance beyond the inner end of the containing sleeve 34. A metal ferrule 37 which is similar in its construction and functions to the ferrule 1 is provided, and this ferrule extends into the outer end of the relatively thin fiber-containing sleeve 34. The ferrule 37 differs from the ferrule 1 however, in that its outer surface is tapered, gradually increasing in diameter from its inner end to its outer end on which the annular flange 38 is formed.

When this modified form of packing is driven into the countersink 39 in the tube sheet 40, additional blows imparted thereto after the inner end of the sleeve 36 engages the shoulder 41 formed at the inner end of the countersink will drive the tapered sleeve 36 into the inner end of the containing sleeve 34 causing radially outward disruption of the sleeve, as indicated at 42 in Figure 9 of the drawings, and forcing such outward radial disrupted portion into recesses in the roughened inner surface of the countersink 39 forming a seal between the sleeve 34 and the tube sheet. Also during such continued blows,

the ferrule 37 will be driven into the outer end of the sleeve 34 causing radially outward disruption of the outer end portions of the sleeve 34 which radial outward disruptions will engage in certain of the recesses of the roughened inner surface of the countersink 39, as shown at 43 of Figure 9 of the drawings. Such additional impact blows will also cause the outward radial disruption of the sleeve 34 at the part which surrounds the soft collapsible packing 33, as shown at 44, thereby providing instantaneous fluid seals between the packing and tube sheet and between the packing and tube which will temporarily prevent leakage until the swelling of the fiber-containing sleeve 34 and fiber rings 35 and 36 complete the permanent seal.

In Figure 11 of the drawings, a modification of the packing structure for the discharge or outlet ends of the tubes is shown which modification corresponds to the modification of the packing for the inlet ends of the tubes such as is shown in Figures 8 to 10 inclusive. The packing structure shown in Figure 11 differs from the packing structures in Figures 5 to 7 only in that the sleeve 45 which engages the inner end of the cylinder 46 of soft collapsible packing has its outer surface tapered as shown at 47 so that when the packing is driven into the countersink in a tube sheet, the inner end of the relatively thin containing portion 48 of the fiber sleeve 49 will be forced outwardly into engagement in some of the recesses formed in the roughened inner surface of the countersink so as to provide a temporary seal such as is formed by the sleeve 36 being driven into the sleeve 34.

The provision of the swellable fiber-containing sleeves, which may be disrupted to form temporary, instantaneous fluid seals and to hold the packing in place when it is initially driven into the countersinks, provides a very distinctive advantage in packings of this type in that it eliminates the need of a very high degree of accuracy in the outer diameter of the packing such as is required when merely fiber sleeves are employed because such disruption action not only serves to hold the fiber packing in place until it swells upon wetting, but it provides a temporary seal against leakage all of which are not provided by single fiber sleeves even in the event that such sleeves are made to the exact dimensions to fit tightly about the tubes and in the countersinks. If the single fiber sleeves are made to fit tightly as to maintain them in place before swelling they will, upon swelling, cause a constriction in the tubes themselves, often resulting in eddies in the fluid flow through the tubes causing excessive pitting or erosion of the tubes.

Figures 13 to 16 inclusive of the drawings show a still further modified form of the packing which embodies substantially the same essential features of the types of packing shown in Figures 1 to 12 inclusive, differing therefrom primarily in the manner in which the soft, pliable packing or corset lacing is held in position prior to the insertion of the packing in a tube sheet.

This modified form of the packing comprises a fiber sleeve 50 which has an annular flange 51 formed on its inner surface, against the outer end of which flange 51 the inner end of the metal ferrule 52 abuts. A cylindrical coil of soft, collapsible packing which may be corset lacing or any other approved material and which carries a lubricant so as to permit not only a firm sealing engagement with the outer surfaces of the tube, but to provide sufficient lubrication to per-

mit the tubes to be driven through the packing or sealing structure without disrupting the fluid-tight seal is inserted into the fiber sleeve 50 with its inner end abutting the outer shoulder formed by the flange 51. The cylindrical coil 53 of soft, collapsible packing is firmly held in position within the fiber sleeve 50 by the crimping of the outer end of the sleeve as shown at 54, thus the packing employed may be assembled into a complete unit ready for use, as shown in section in Figure 14 of the drawings, when it is placed on the market, and it may be quickly inserted into the countersink formed in any type of tube sheet 56 about the tube receiving opening 57. When the packing structure is driven into the countersink 55 and the inner crimped end of the sleeve 50 engages the inner end 58 of the countersink further driving inwardly of the packing will cause an outward disruption of the sleeve, as shown at 59 so as to provide an initial seal about the tube and to hold the packing in place.

It will be understood that the invention is not to be limited to the specific construction or arrangement of parts shown, but that they may be widely modified within the invention defined by the claims.

What is claimed is:

1. In a heat exchanger, tube sheets, fluid circulating tubes, said tube sheets provided with openings to receive the ends of said tubes and with countersinks about said openings terminating in internal annular shoulders, the walls of said countersinks being roughened, packing for forming a fluid-tight seal between the tubes and tube sheets, each tube packing including a thin fiber confining sleeve swellable when wetted which sleeve is distorted radially outwardly into the recesses of the roughened portion of the countersinks when driven thereto.

2. In a heat exchanger, tube sheets, fluid circulating tubes, said tube sheets provided with openings to receive the ends of said tubes and with countersinks about said openings terminating in internal annular shoulders, the walls of said countersinks being roughened, packing for forming a fluid-tight seal between the tubes and tube sheets, each tube packing including a cylinder of soft collapsible packing, a thin fiber confining sleeve swellable when wetted about said soft collapsible packing, and means engaging the ends of said cylinder of soft collapsible packing for confining it in said sleeve.

3. In a heat exchanger, tube sheets, fluid circulating tubes, said tube sheets provided with openings to receive the ends of said tubes and with countersinks about said openings terminating in internal annular shoulders, the walls of said countersinks being roughened, packing for forming a fluid-tight seal between the tubes and tube sheets, each tube packing including a cylinder of soft collapsible packing, a thin fiber confining sleeve swellable when wetted about said soft collapsible packing, and means engaging the ends of said cylinder of soft collapsible packing for confining it in said sleeve, said thin fiber sleeve being of such thickness and composition that upon driving in a countersink it will become radially outwardly distorted into certain of the recesses of the roughened portion of the countersink.

4. In a heat exchanger, tube sheets, fluid circulating tubes, said tube sheets provided with openings to receive the ends of said tubes and with countersinks about said openings terminating in internal annular shoulders, the walls of

said countersinks being roughened, packing for forming a fluid-tight seal between the tubes and tube sheets, each tube packing including a cylinder of soft collapsible packing, fiber washers at each end of said soft collapsible packing and a thin fiber confining sleeve swellable when wetted about said soft collapsible packing and said fiber washers, said thin fiber sleeve being of such thickness and composition that upon driving in a countersink it will become radially outwardly distorted into certain of the recesses of the roughened portion of the countersink.

5. In a heat exchanger, tube sheets, fluid circulating tubes, said tube sheets provided with openings to receive the ends of said tubes and with countersinks about said openings terminating in internal annular shoulders, the walls of said countersinks being roughened, packing for forming a fluid-tight seal between the tubes and tube sheets, each tube packing including a cylinder of soft collapsible packing, fiber washers at each end of said soft collapsible packing and a thin fiber confining sleeve swellable when wetted about said soft collapsible packing and said fiber washers, said thin fiber sleeve being of such thickness and composition that upon driving in a countersink it will become radially outwardly distorted into certain of the recesses of the roughened portion of the countersink, and a ferrule extending into the outer end of said thin fiber sleeve, said ferrule having an annular driving flange on its outer end.

6. In a heat exchanger, tube sheets, fluid circulating tubes, said tube sheets provided with openings to receive the ends of said tubes and with countersinks about said openings terminating in internal annular shoulders, the walls of said countersinks being roughened, packing for forming a fluid-tight seal between the tubes and tube sheets, each tube packing including a cylinder of soft collapsible packing, a thin fiber confining sleeve swellable when wetted about said soft collapsible packing, a fiber ring extending into the inner end of said sleeve and being tapered whereby when the packing is driven into position in a countersink the inner end of said sleeve will be expanded into recesses of the roughened surface of the countersink.

7. In a heat exchanger, tube sheets, fluid circulating tubes, said tube sheets provided with openings to receive the ends of said tubes and with countersinks about said openings terminating in internal annular shoulders, the walls of said countersinks being roughened, packing for forming a fluid-tight seal between the tubes and tube sheets, each tube packing including a cylinder of soft collapsible packing, a thin fiber confining sleeve swellable when wetted about said soft collapsible packing, a fiber ring extending into the inner end of said sleeve and being tapered whereby when the packing is driven into position in a countersink the inner end of said sleeve will be expanded into recesses of the roughened surface of the countersink, and a ferrule in the outer end of said thin fiber sleeve and being tapered whereby when the packing is driven into position in a countersink said thin fiber sleeve will be expanded into recesses of the roughened surface of the countersink.

8. In a heat exchanger, tube sheets, fluid circulating tubes, said tube sheets provided with openings to receive the ends of said tubes and with countersinks about said openings terminating in internal annular shoulders, the walls of said countersinks being roughened, packing for

forming a fluid-tight seal between the tubes and tube sheets, each tube packing including a cylinder of soft collapsible packing, a thin fiber confining sleeve swellable when wetted about said soft collapsible packing, a ferrule extending into the outer end of said sleeve and having its outer surface tapered whereby when the packing is driven into position in a countersink the outer end of said sleeve will be expanded into recesses of the roughened surface of the countersink.

9. A packing for heat exchanger tubes comprising, a thin fiber sleeve swellable when wetted, soft collapsible packing within said fiber sleeve and adapted to engage a tube when in packing association therewith, and means within the sleeve and engaging said packing for retaining the packing within the sleeve.

10. A packing for heat exchange tubes comprising, a fiber sleeve swellable when wetted, soft collapsible packing within said fiber sleeve and adapted to engage a tube when in packing association therewith, and means formed upon said sleeve and engaging said soft collapsible packing for retaining it within the sleeve.

11. A packing for heat exchange tubes comprising, a fiber sleeve swellable when wetted, soft collapsible packing within said fiber sleeve, a portion of said sleeve surrounding said collapsible packing being thinner than some other portions of the sleeve, whereby when the packing is driven into an opening and in endwise engagement with an abutment the thin portion of the sleeve surrounding a collapsible packing will be distorted outwardly.

12. A packing for heat exchange tubes comprising, a fiber sleeve swellable when wetted, soft collapsible packing within said fiber sleeve, a portion of said sleeve surrounding said collapsible packing being thinner than some other portions of the sleeve, whereby when the packing is driven into an opening and in endwise engagement with an abutment the thin portion of the sleeve surrounding the collapsible packing will be distorted outwardly, and means within said sleeve and engaging said packing for retaining it within the sleeve.

13. A packing for heat exchanger tubes comprising, a thin fiber sleeve swellable when wetted, soft collapsible packing within said fiber sleeve, means within the sleeve and engaging said packing for retaining the packing within the sleeve, and said packing retaining means serving to reinforce the portions of the sleeve on each side of the packing whereby when the packing is driven into an opening and in endwise engagement with an abutment the portion of the sleeve surrounding the collapsible packing will be distorted outwardly.

14. A packing for heat exchange tubes comprising, a fiber sleeve swellable when wetted, soft collapsible packing within said fiber sleeve, and means for reinforcing said fiber sleeve at each end of said collapsible packing whereby when the

packing is driven into an opening and in endwise engagement with an abutment a portion of the sleeve surrounding the collapsible packing will be distorted outwardly.

5 15. A packing for heat exchange tubes comprising, a fiber sleeve swellable when wetted, soft collapsible packing within said fiber sleeve and adapted to engage a heat exchange tube when in packing association therewith, one end of said fiber sleeve being inturned to form an annular flange for confining said soft collapsible packing in the sleeve.

15 16. A packing for heat exchange tubes comprising, a fiber sleeve swellable when wetted, soft collapsible packing in said sleeve and adapted to engage a heat exchange tube when in packing association therewith, a tapered sleeve extending partly into one end of said fiber sleeve whereby when the tapered sleeve is driven into the fiber sleeve the latter will be disrupted radially outwardly.

20 17. A packing for heat exchange tubes, comprising a fiber sleeve swellable when wetted, soft collapsible packing in said sleeve and adapted to engage a heat exchange tube when in packing association therewith, a tapered sleeve extending partly into one end of said fiber sleeve whereby when the tapered sleeve is driven into the fiber sleeve the latter will be disrupted radially outwardly, and said soft collapsible packing will be compressed and distorted radially inwardly towards its axis.

25 18. A packing for heat exchange tubes comprising, a fiber sleeve swellable when wetted, soft collapsible packing within said fiber sleeve and adapted to engage a heat exchange tube when in packing association therewith, a portion of said sleeve surrounding said collapsible packing being thinner than some other portions of the sleeve, whereby when the packing is driven into an opening and in endwise engagement with an abutment the thin portion of the sleeve surrounding a collapsible packing will be distorted outwardly, and said soft collapsible packing will be compressed and distorted radially inwardly towards its axis.
